UNITED STATES PATENT OFFICE

RICHARD NERLICH, OF BERLIN, GERMANY

OBJECTIVE SHUTTER

Application filed November 21, 1929, Serial No. 408,852, and in Germany November 23, 1928.

This invention relates to an objective shutter intended principally for photographic exposing apparatus for making series pictures of tracts of land from a flying machine. This 5 shutter is provided with two oscillable semi-circular shutting members forming together a circular shutting member proper which may be located in front of, or behind, or inside, the objective. Said semi-circular members form, or are attached to, the ends of two lever-like arms connected with one another in known manner by a toggle-joint lever. This known arrangement and combination of parts has been improved, according to this 10 invention, as follows:

The middle pivot of the toggle lever which projects over the arms of this lever at their junction and is guided with this projecting end in a slot of a sleeve is utilized as a means 20 for damping the shutter halves at the very last portion of their closing path, the object of this damping being the obviation of defective exposures. The object in view is attained best by combining with said pivot 25 a piston guided in said sleeve which forms at its lower end a cylinder in which the quickly descending piston compresses air at the end of its path and is thereby quickly, as well as softly, intercepted.

30 The invention is illustrated diagrammatically and by way of example on the accompanying drawings, on which Figure 1 is a front view of a shutter designed according to this invention, only one frame part (of 35 which portions are visible in the middle parts of Figs. 2 and 3) being omitted in order to show more distinctly the parts located therebehind; Figure 2 is a similar view showing some of the movable parts in another position; Figure 3 shows certain of these parts in 40 still another position, and Figure 4 is a vertical section through the middle of the device, all as fully described hereinafter.

45 a and a' are two semicircular shutting members proper. They are shown closed in Figs. 1 and 3, and open in Fig. 2 and they are secured to the ends of oscillable arms b and b' movably suspended at c and c' at the rear wall d of the shutter frame. The members 50 a and a' , as well as b and b' , are arranged

symmetrically with respect to the axis of the objective and are moved towards, as well as away from, one another by means of the arms e e' of a toggle-joint lever which are connected with the arms b b' by means of pivots 55 f f' , and with one another by means of a pivot g . This pivot is located in a piston h which is guided in a sleeve i having at its front face a vertical slot i' into which extends the forwardly projecting end of the pivot g . 60 The piston h is laterally slotted, and the inner ends of the toggle-joint lever arms extend through these slots into the interior of the piston where they are connected with this latter and with one another by means of 65 the pivot g .

The toggle-joint lever arms e e' are subjected to the pull of oblique helical tensile springs j connected at their upper ends with said arms and at their lower ends with the 70 rear plate of the frame. These springs tend continually to hold the arms e e' in the position shown in Fig. 1. When these arms are in this position, the position of the shutters arms b b' is such that the shutter members proper a a' are in their shutting position, as in Fig. 1.

In front of the shutter arms b b' is located a lever r which is fulcrumed at p to the rear frame plate d or, more precisely, to a projection of said plate so that the lever r lies somewhat remote from the said plate, viz. just in front of the slotted sleeve i which it crosses below the projecting end of the toggle-joint pivot g (Figs. 1 and 2).

80 From the upper end of the sleeve i is suspended on a pivot k a bell-crank lever consisting of a shorter arm m and a longer arm m' . The shorter arm is designed as a pawl m^2 and the longer arm is connected with a helical tensile spring o tending to hold the lever m m' in such a position that the pawl m^2 extends over the slot i' , viz. over the upper 85 end thereof, as in Fig. 2. Normally, however, the spring o is prevented from holding said bell-crank lever in said position, in that the arm m' of this lever is subjected to the action, i. e. pressure, of a pin r' extending forth forwardly from an upwardly directed extension forming a part of the lever r , near 90

95 100

the fulcrum p thereof. In the normal position, or position of rest, of the parts concerned their position is that shown in Fig. 1 in which the pawl m^2 does not cover the slot i' of the piston guiding member i . In this position of the parts the shutter is closed.

When the shutter is to be actuated (for momentary exposure or exposures), the lever r is turned in the direction indicated by the arrow shown at the lefthand side of Fig. 1, whereby the toggle-joint junction pin or pivot g will be lifted, in consequence whereof the toggle-joint arms $e\ e'$ will be moved asunder, as will also the shutter arms $b\ b'$ and the shutter members proper $a\ a'$, the position being then that shown in Fig. 2. But this is merely a medium position. While the lever r has been turned, as just described, its pin r' has at a certain point of its path left the arm m' of the bell-crank lever $m\ m'$ and prior thereto the spring o has turned this lever so that its pawl m^2 has finally arrived over, or in front of, the slot i' . While the lever r is further turned upwardly, the position of the toggle-joint lever arms is reversed (Fig. 3) and finally the pin or pivot g contacts with the pawl m^2 and passes along and over it, during which time the pawl is first pressed back and then re-assumes automatically (under the pull of the spring o) its former position, that is to say, that position in which its active portion lies over the slot i' . In this moment the pivot g is locked by the active pawl portion (Fig. 3), and when now the lever r is released or dropped it falls back into a certain medium position, viz. that in which its pin r' again contacts with the arm m' of the bell-crank lever $m\ m'$, as in Fig. 3.

While the lever r had been moved from the position Fig. 1 into the position Fig. 3, the shutting members $a\ a'$ has been opened and closed, and simultaneously therewith the springs $j\ j$ have been expanded (Fig. 3). The device is now in its operative position for momentary exposure, and the operation for making such an exposure, i. e. the next actuation of the device, consists merely in further depressing the lever r so that the pin r' presses upon the arm m' of the bell-crank lever and turns thereby this lever, in consequence whereof the pawl m^2 will be withdrawn from the pin or pivot g . Now the expanded springs j can become operative, and they now stretch instantaneously the toggle-joint lever (position Fig. 2, in which the shutter arms $b\ b'$ are moved away from one another, as are consequently, also the shutter members proper $a\ a'$) and turn them in the next moment to an angle (position Fig. 1, in which the position of the parts $a\ a'$ and $b\ b'$ is the same as in Fig. 3). In other words: the shutter has been opened a very short time, a fraction of a second, and a momentary exposure has been made in that fraction.

It need hardly be said that together with the toggle-joint junction pin or pivot g also the piston e has been torn downwardly very quickly by the springs j , and on the very last portion of its path it has entered into the damping cylinder i^2 whereby the damping intended is attained. The strength of this damping action can, if desired, be regulated by providing the cylinder i^2 with an air-escape regulating screw, or any equivalent provision may be made. In every case the shutter members proper $a\ a'$ are prevented, by the damping, from even the slightest rearward movement after they have arrived in their end position in which the shutter is completely closed, and this being so, defective exposures are completely prevented.

I claim:

1. An objective shutter of the character described, comprising, in combination, a pair of oscillable arms adapted to be moved towards, and away from, one another and forming at their free ends the shutting members proper for the objective; a toggle-joint lever located between said arms and being connected with them; springs engaging the toggle-joint lever arms and tending to maintain said shutter members proper in closed position; a slotted longitudinal member also located between the oscillable arms and behind said toggle-joint lever, the middle junction pivot of this lever engaging said slot; and damping means so arranged as to be adapted to intercept the said shutter members proper just before the very end of their closing path.

2. An objective shutter of the character described, comprising, in combination, a pair of oscillable arms adapted to be moved towards, and away from, one another and forming at their free ends the shutting members proper for the objective; a toggle-joint lever located between said arms and being connected with them; springs engaging the toggle-joint lever arms and tending to maintain said shutter members proper in closed position; a slotted longitudinal member also located between the oscillable arms and behind said toggle-joint lever, the middle junction pivot of this lever engaging said slot; and means so arranged with respect to said pivot as to intercept it just before the end of its downward path and to stop thereby elastically also the other movable members connected with it directly and indirectly, substantially as set forth.

3. An objective shutter of the character described, comprising, in combination, a pair of oscillable arms adapted to be moved towards, and away from, one another and forming at their free ends the shutting members proper for the objective; a toggle-joint lever located between said arms and being connected with them; springs engaging the toggle-joint lever

arms and tending to maintain said shutter members proper in closed position, the lowermost portion of this member being designed as a cylinder, and the said member being also located between the oscillable arms and behind said toggle-joint lever, the middle junction pivot of this lever engaging said slot; a piston located in the slotted longitudinal member and being connected with said pivot, this latter being adapted to damp elastically the movable members connected directly and indirectly with it just prior to said shutting members proper arriving in their closed position.

15 4. An objective shutter of the character described, comprising, in combination, a pair of oscillable arms adapted to be moved towards, and away from, one another; semi-circular shutting members proper attached to the free ends of said arms; a toggle-joint lever located between the said arms and being connected with them; springs engaging said toggle-joint lever and tending to keep said shutting member proper in closed position; a sleeve arranged between the oscillable arms behind said toggle-joint lever and having a longitudinal slot receiving the middle junction pivot of the toggle-joint lever arms and guiding directly said pivot and the movable parts connected therewith; a piston-like member arranged within said sleeve and being connected with the said pivot and adapted to be moved upwardly and downwardly in the said sleeve in correspondence with the toggle-joint lever arms and the parts connected with them; a cylinder constituting the lowermost end of the said sleeve and forming a damping space for said piston when this latter arrives at the very end of its path, substantially as set forth.

45 5. An objective shutter of the character described, comprising, in combination, two practically parallel one-armed levers terminating at the objective; semi-circular objective shutting members attached to the ends of said levers and forming together the shutter proper for the objective; a sleeve arranged between said levers practically parallel to them and having a slot at its front 50 face and forming a cylinder at that end which is located near the objective; a piston arranged in said sleeve; toggle-joint lever arms arranged in front of said slot and being connected with the middle junction pin of the 55 toggle-joint lever; and springs engaging the toggle-joint lever arms and tending to turn them so as to keep the shutter proper closed, substantially as set forth.

60 In testimony whereof I affix my signature.
RICHARD NERRLICH.
